(57) **CLAIM**

The ornamental design for an anti-leakage sanitary napkin, as shown and described.

DESCRIPTION

FIG. 1 is a top, front and left side perspective view of an anti-leakage sanitary napkin showing my new design; FIG. 2 is a top, front and right side perspective view thereof; FIG. 3 is a top, rear and left side perspective view thereof; FIG. 4 is a front elevational view thereof; FIG. 5 is a rear elevational view thereof; FIG. 6 is a left side view thereof; FIG. 7 is a right side view thereof; FIG. 8 is a top plan view thereof; FIG. 9 is a bottom plan view thereof; FIG. 10 is an enlarged view of portion 10 in FIG. 1; FIG. 11 is an enlarged view of portion 11 in FIG. 1; and, FIG. 12 is an enlarged view of portion 12 in FIG. 1. The long dash-short dash broken line circles in the figures depict the bounds of the enlarged portions of the anti-leakage sanitary napkin and form no part of the claimed design.

1 Claim, 12 Drawing Sheets
